UNITED STATES PATENT OFFICE

2,500,803

SECTIONAL GRAIN PAN FOR THRESHING MACHINES

Dennis Cockrell, Durham, Okla.

Application November 5, 1947, Serial No. 784,155

3 Claims. (Cl. 130—24)

1

My present invention relates to the general class of threshing implements, including grain separators, straw carriers, and shaking tables or oscillating and reciprocating grain-pans, and more specifically to an improved adjustable grain-pan support or attachment for mounting the grain-pan within the separator housing of an automotive combine, a mobile thresher, or a tractor-towed thresher.

The primary object of the invention is the provision of supporting mechanism for a hinged oscillating grain-pan by means of which the suspended or floating pan may oscillate or reciprocate smoothly without excessive shocks or vibrations of the operating parts, to insure a more efficient performance of the functions of the shaker table or grain-pan.

The attachment of my invention includes a minimum number of parts that may be manufactured with facility at low cost of production, and the parts may be assembled with convenience for installation with various well known types of threshing machines without material alteration of the machines, to enhance their proficiency.

The invention consists in certain novel combinations and arrangements of parts for mounting the suspended grain-pan within the separator housing as will hereinafter be described and more particularly set forth in the appended claims.

In the accompanying drawings I have illustrated one complete example of an installation of a physical embodiment of my invention in which the parts are combined and arranged in accord with one mode I have devised for the practical application of the principles of my invention.

It will be understood that changes and alterations are contemplated and may be made in these exemplifying drawings and mechanical structures, within the scope of my claims without departing from the principles of the invention.

Figure 1 is an exterior side elevation of a portion of a thresher or combine showing the separator housing, and equipped with the adjustable supports of my invention for the interior grain-pan; and

Figure 2 is a vertical longitudinal sectional view of the structure in Fig. 1 equipped with the mechanism of my invention.

Figure 3 is a transverse vertical sectional view at line 3—3 of Fig. 1, with parts omitted to more clearly show the application of the mechanism of my invention.

2

Figure 4 is an enlarged detail view in side elevation at the hinged joint of the sectional grain-pan.

Figure 5 is a detail view in elevation of one of the two complementary supports for the grain-pan.

Figure 6 is a detailed vertical, sectional view of the support.

Figure 7 shows one of the hinge bolts or pins of the grain pan and

Figures 8 and 9 are respectively a face view and an edge view of one of the reinforcing or wear plates which protect the sides of the machine on which my invention is installed during the movement of the hinge bolts caused by the oscillation and reciprocation of the grain-pan.

In order that the general arrangement and utility of parts may readily be understood, I have shown in the assembly views, so much of the grain separating portion of the housing of a thresher which is generally designated by the reference numeral 1 as is necessary for an appreciation of the merits of my invention. This portion of the thresher includes the conventional

separator housing in which the sectional or hinged grain-pan or shaker table is mounted, and the sections are designated as 2 and 2A respectively.

The section 2 is the rear section, and the section 2A is the front section. The hinged grain-pan

is suspended at its ends, as usual on pivoted hangers 3 and 4, and the pan is oscillated and reciprocated in a horizontal plane to separate the material that is fed thereto from the rotary cylinder 5, and passing through the concave 6, is deposited on the oscillating pan.

The air blast caused by the usual rotary fan 7 passing through the passage 8 of the fan housing separates the chaff from the grain as it flies over the chaffer 10. The grain-pan section 2 is provided with the chaffer fingers 9, overlying the chaffer 10 and sieve 11, located beneath the chaffer 10.

In Fig. 1, the rotary operating parts such as the cylinder 5 and fan 7 are actuated from a belt drive 12, and the grain-pan sections 2 and 2A are oscillated by power transmitted from a chain drive 13 in connection with a pitman mechanism 14, pitman 15, and the pivoted rocker arm 16 pivotally connected to the grain-pan section 2, as shown in Figure 2.

In carrying out my invention, the hinged and pivotally suspended oscillating and reciprocating grain-pan sections 2 and 2A are, in addition to the hangers 3 and 4, provided with a supporting mount at the axially aligned hinge joints, and a

pair of these mounts is provided, one at each exterior side of the housing 1. Inasmuch as the two mounts are similar in construction and operation, a detailed description of one will suffice for both mounts.

The hinge joints, between the two sections 2 and 2A of the grain-pan usually include a horizontally disposed truss head rivet. My invention contemplates the removal of this conventional rivet, and replacing it with a hardened steel bolt 17 that passes through the section 2A of the grain-pan and is supported in the apertured ear or hinge plate 19 bolted at 18 on the hinged end of the section 2.

This outwardly extending bolt is received in a cylindrical bearing bushing 20 that passes through an arcuate slot in the side wall of the housing 1, and the wall of the slot is reinforced by means of a hardened metal reinforcing or wear plate 21 having an arcuate slot 22, and bolted on the housing.

The reinforcing or wear plate 21 prevents the movement of the bolt and its bushing from wearing the slot in the housing as the floating grain pan is oscillated and reciprocated with flexing movements of the hinge joint, and the grain-pan is supported to insure smooth operation and to absorb shocks and strains of the vibrating parts.

At its outer end, the bushing 20 is provided with an integral depending arm 23 that is threaded at its lower end into a boss 24 having a complementary threaded socket 33 in which the arm is adjustably connected, and the boss is integral with a bearing bushing 25. When properly adjusted, the arm is locked in adjusted position by means of a pair of lock nuts 26 and 27 threaded on the arm and against the upper end of the boss 24.

The arm 23 rocks with the complementary movements of the grain-pan, and for this purpose the bushing 25 is journaled upon a supporting bolt or pin 28 that is passed through a bearing hole in a base plate 29 that is bolted at 30 on the exterior face of the housing; lock nuts 31 and 32 being employed on the pivot bolt for retaining the arm assembly in operative position.

It has been found by operators of the particular type of machine on which my invention is installed that the conventional rivet causes wear at the hinged joint of the grain-pan sections. This wear results in vibration and slap of the section, which causes serious trouble and damage to the grain-pan section.

The installation of my invention prevents wear of the grain-pan sections, as it supports these sections at the hinged joint during the oscillation and reciprocation of the sections. The grain-pan sections float smoothly on the hanger, and the hanger is adjustable to compensate for any wear that may occur.

It is believed that from the foregoing description, the manner of mounting and the construction of my hanger will be apparent to those skilled in the art.

Having thus fully described my invention, what

I claim as new and desire to secure by Letters Patent is:

1. In a thresher including a separator housing having side slots and exterior slotted wear plates fixed about the slots, the combination with two opposed pairs of pivoted depending hangers mounted on the exterior of the housing, a sectional grain pan having the outer ends of the sections pivotally connected to the hangers and the inner ends extending toward each other and pivotally connected to each other, and means for longitudinally reciprocating the pan, a pair of pivot pins for connecting the inner ends of the sections and projecting through the slots, a pair of upstanding supporting arms pivotally mounted at their lower ends on the exterior of the housing, a pair of bushings rigid with the upper ends of the arms and enclosing the pins, means for retaining the bushings on the pins, and means for longitudinally adjusting the arms in relation to the pivot pins.

2. In a thresher including a separator housing having slots in the side walls and slotted wear plates fixed about the slots, the combination with two opposed pair of pivotally depending hangers mounted on the exterior of the housing, a sectional grain pan, the sections of said grain pan being pivotally connected to the hangers at their outer ends and extending inwardly of the hangers and terminating intermediate thereof, pivot pins for pivotally connecting the inner ends of the sections of said grain pan to each other, and said pivot pins projecting through said slots, a pair of upstanding adjustable supporting arms pivotally mounted at their lower ends on the exterior of the housing, a pair of bushings rigid with the upper ends of the arms and enclosing the pins, means for retaining the bushings on the pins and means for retaining the arms in various adjustable positions.

3. In a threshing machine, a separator housing, a grain pan within the housing having front and rear sections, hangers pivoted at their upper ends to the housing and at their lower ends to the remote ends of the pan sections, pivot pins connecting the adjacent ends of the pan sections, supporting arms pivoted at their lower ends to the housing and at their upper ends to the pivot pins and means for longitudinally reciprocating the pan.

DENNIS COCKRELL.
